UNITED STATES PATENT OFFICE.

DANIEL TAYLOR, OF LAWRENCE, MASSACHUSETTS.

MACHINE FOR STRAIGHTENING DROP WIRES.

Application filed May 19, 1925. Serial No. 31,323.

To all whom it may concern:

Be it known that I, DANIEL TAYLOR, a citizen of the United States, residing at Lawrence, in the county of Essex and State of Massachusetts, have invented certain new and useful Improvements in Machines for Straightening Drop Wires, of which the following is a specification.

This device relates to machines for straightening certain classes of wires or metal strips, without heating.

It is particularly useful for straightening what are known as drop wires, which are used in connection with warp stop motions on looms.

These wires are made of mild steel with light temper, and are of an elongated U-shape with two long legs at one end and a loop at the other end.

On account of the operation of the machinery one or both legs are frequently bent so that the wire becomes useless unless this bend can be straightened out. This cannot be done in a satisfactory manner by hammering or by any other method, and the wires are therefore thrown away.

My machine is devised for the purpose of straightening wires, and particularly drop wires, as the old wires have become smooth by use and are more satisfactory than new wires, and my machine permits wires to be continuously used until they are entirely worn out.

In the drawings, Fig. 1 is a plan view of my preferred type of machine shown attached to a table, and with a drop wire in position, having one leg bent and about to be straightened.

Fig. 2 is a vertical sectional view, substantially on line 2—2 of Fig. 1, some parts being omitted for clearness.

Fig. 3 is a view similar to Fig. 2 showing a drop wire in position about to be straightened, and also its position shown by dotted lines after it is straightened.

Fig. 4 is a view from the side, on which is the operating handle showing a slight modification of the pulling handle.

Fig. 5 is a sectional view on line 5—5 of Fig. 1, looking in the direction of the arrow.

Fig. 6 is a sectional view on line 6—6 of Fig. 5, showing one position of the cam and jaws, in the open position.

Fig. 7 is a view similar to Fig. 6, showing the cams and jaws in the closed position.

In the drawings, T represents a table hav-

ing an end 22 to which, by means of a bolt 6, and wing nut 7, the base B is firmly fastened.

A represents a drop wire having the flat legs 10, 11, and 13, and elongated hole 12.

C represents a fixed jaw attached to base B by means of a plate 32 and screws 33, 33. Jaw C has spaced teeth 30, the ends of which are preferably smooth and rounded and which are alined.

D represents a movable jaw which is slideable on base B under a plate 42 which is fixed to base B by screws 43.

The returning spring E at one end has a loop 38 by which it is affixed to one of the screws 33, and its other end 48 is bent down vertically into a hole 148 in movable jaw D.

I provide near one end of jaws C and D, which I will call the entering end, means for advancing that end of the movable jaw towards the fixed jaw, which I will call pressure means.

This includes post 49 which passes into and is revoluble in a hole 149, in base B, and this is cut away adjoining jaw D, to form a cam 41.

A pressure handle K is fixed to 49 above cam 41 by means of nuts 1 and 2, the end of post 49 at 147 being so formed as to make handle K and post 49 turn together.

This pressure handle K is so adjusted that when the jaws C and D are open it projects diagonally beyond the side 8 of block B, and it has a depending end 4 which, when the jaws are closed, extends down just outside the back end 112 of base B.

As shown in Fig. 1, it is also cut away at 3 so that when the pulling handle H is operated, it will move pressure handle K from the full line open position shown in Fig. 1, to the dotted or closed position.

N is a hook which I call gripping means as it can be passed through hole 12 in a drop wire A, and as it is attached to a chain G, which I will call pulling means, it will pull the drop wire between the teeth of the jaws when the chain G is pulled.

This chain G is attached to a staple 52 on a barrel 53 fixed to the pivot shank 54 of pulling handle H. 55 is the main shank of H, and 56 the handle.

When this handle H is turned from the full line position in Figs. 1 and 2, to the dotted line position, it revolves barrel 53, pulls chain G and hook N, and draws the wire A between the alined teeth 40 and 30.

These teeth 40 and 30 are each positioned

so that teeth 30 are opposite the spaces between teeth 40, and vice versa.

The operation is as follows:

A bent drop wire is placed between the 5 jaws when they are opened, as shown in Fig. 6, and hook N is attached thereto.

The jaws are now closed by operating the 10 handle K manually, or preferably by the pressure of the shank 55 of handle H on the cut away part 3 of handle K, these being so adjusted that they will co-operate.

The handle H may be shaped as shown in Fig. 4 at P, being pivoted at 80 and having the handle end 81 while the part 82 between 15 them bends down and up, and extends out opposite the end of K whereby the cut away part 3 is unnecessary.

On account of the fact that the cam which forces the jaws together is nearer the entering end than the delivery end, the pressure 20 on the wire is greatest at the entering end, and at the delivery end is just sufficient to release it gradually, and without creating any final kink.

25 The tips of the teeth or jaw are alined, and their faces are preferably rounded.

At the entering side of the jaws, when the handle K is operated the teeth slightly intersect and slightly crimp the wire, while at the 30 other end they barely touch each side of the wire so that it can be released without difficulty.

There may be a slight pivotal action at the end 48 of the wire spring E but the tendency 35 is to force the exit end of the jaws apart and keep the entrance end together.

I prefer that the height of each jaw should be a trifle over the height or width 40 of each leg as I prefer to straighten one leg at a time, but it is obvious that the jaws might be high enough to take in both legs at a time.

The pulling of the wire should be directly in line with the space between the jaws, but 45 this is taken care of with my flexible chain which serves as a pulling member.

I claim:

1. In a wire straightening machine, the combination with a base; of a jaw fixed 50 thereto which has spaced teeth the tips of which are alined; a second jaw slidable on the base to and from the first jaw, such second jaw having spaced teeth the tips of which are alined and are positioned opposite the spaces between the teeth of the first jaw; pressure means near the entering end of the second jaw to advance that end towards, and retract it from, the first jaw; a handle for the pressure means; gripping means to seize a wire proximate the delivery end of the jaws; pulling means to move said gripping means away from the jaws; and a handle connected to the pulling means to operate said pulling means.

operate said pulling means, so arranged as to also operate the handle for the pressure 65 means.

2. In a wire straightening machine, the combination with a base; of a jaw fixed thereto which has spaced teeth the tips of which are alined; a second jaw slidable on 70 the base to and from the first jaw, such second jaw having spaced teeth the tips of which are alined and are positioned opposite the spaces between the teeth of the first jaw; pressure means near the entering end of the second 75 jaw to advance that end towards, and retract it from, the first jaw; a handle for the pressure means; gripping means to seize a wire proximate the delivery end of the jaws; pulling means to move said gripping 80 means away from the jaws; and a handle connected to the pulling means to operate said pulling means.

3. In a wire straightening machine, the combination with a base; of a jaw fixed 85 thereto which has spaced teeth the tips of which are rounded and alined; a second jaw slidable on the base to and from the first 90 jaw, such second jaw having spaced teeth the tips of which are rounded and alined and are positioned opposite the spaces between the teeth of the first jaw; pressure means near the entering end of the second jaw to advance that end towards, and retract it from, the first jaw; a handle for the 95 pressure means; gripping means to seize a wire proximate the delivery end of the jaws; pulling means to move said gripping means away from the jaws; and a handle connected to the pulling means to operate said pulling 100 means.

4. In a wire straightening machine, the combination with a base; of a jaw fixed thereto which has spaced teeth the tips of which are rounded and alined; a second jaw 105 slidable on the base to and from the first jaw, such second jaw having spaced teeth the tips of which are rounded and alined and are positioned opposite the spaces between the teeth of the first jaw; pressure means near the entering end of the second 110 jaw to advance that end towards, and retract it from, the first jaw; a handle for the pressure means; gripping means to seize a wire proximate the delivery end of the jaws; pulling means to move said gripping means 115 away from the jaws; a returning spring for the movable jaw having an end which is pivotally connected to the movable jaw between the pressure means and the gripping means; and a handle connected to the pulling means to operate said pulling means, so arranged as to also operate the handle for the pressure means.
